BABY PLATE

Jack L. Day, Hayward, Calif.

Application January 27, 1950, Serial No. 7,512

Term of patent 14 years

(Cl. D44—15)

To all whom it may concern:

Be it known that I, Jack L. Day, a citizen of the United States, residing at Hayward, in the county of Alameda and State of California, have invented a new, original, and ornamental Design for a Baby Plate, of which the following is a specification, reference being had to the accompanying drawing, forming part thereof.

Fig. 1 is a top plan view of a baby plate showing my new design;

Fig. 2 is a rear elevational view;

Fig. 3 is a bottom plan view;

Fig. 4 is a sectional view taken on line 4—4 of Fig. 1 and

Fig. 5 is a side elevational view thereof.

I claim:

The ornamental design for a baby plate, substantially as shown.

JACK L. DAY.
